UNITED STATES PATENT OFFICE.

BENJAMIN C. MEYER, OF NEY, OHIO.

RAILWAY-CROSSING.

No. 926,672.

Specification of Letters Patent. Patented June 29, 1909.

Application filed April 2, 1909; Serial No. 427,447.

To all whom it may concern:

Be it known that I, BENJAMIN C. MEYER, a citizen of the United States, residing at Ney, in the county of Delaware, State of Ohio, have invented new and useful Improvements in Railway-Crossings, of which the following is a specification.

My invention relates to railway track crossings, and has for its object to provide certain improvements in the same whereby a novel means is provided for shifting the rail sections at the crossing of two lines to alternately open or close one line and to simultaneously close or open the other line. This object I accomplish in the manner and by the means hereinafter described and claimed, reference being had to the accompanying drawing, in which:

Figure 1 is a plan view of my improved crossing. Fig. 2 is a detail sectional view on the line II--II, Fig. 1.

Similar numerals of reference denote corresponding parts in the two views.

In the said drawing the reference numerals 1 denote the fixed tracks running in one direction, and 2 the fixed tracks of the crossing line, all of the same being mounted upon a base frame 3. Also movable on said base frame 3 are the movable rail sections 4 and 5 for the two lines. Said rail sections are two in number for each rail, and are bodily movable on the base frame 3. The two rail sections for each rail of the lines are pivotally connected to each other at their adjoining ends by a plate 6 that is centrally pivoted at 7 to the base frame 3. Pivotally connected to said plates 6 are links 8, all of which extend to and are pivotally connected at their inner ends to a center plate 9 pivoted at 10 to the base frame 3. Also pivoted at 11 to the base frame 3 is a lever 12 that extends past the other side of said base frame, where it may be connected with suitable operating means, said lever being connected intermediate its length to said center plate 9 by means of a short link 13.

Fixed to the base frame 3 is a series of stops 14, there being three for each movable rail section 4 and 5, said stops being undercut on their sides adjacent to their rail sections to receive the flanges of said rails. The two rail sections 4 and 5 of each pair move in opposite directions at their adjoining ends, and the stops 14 for each rail section are disposed two upon the side opposite to that of the movement of their rail section,

and one upon the other side near its end opposite to that connected with its plate 6, as shown.

The operation of the device is as follows: With the parts in the position shown in full lines in Fig. 1 the rail section 5 is in alignment with their rails 2, and that track is ready for the passage of a train, the rail sections 4 being moved inward to be out of the path of travel of the wheel flanges of a passing train. To reverse the position of the parts the lever 12 is shifted to the right to the dotted line position, which through short link 13 partially rotates center plate 9 on its pivot 10, thereby through links and pivoted plates 6 bringing the rail sections 4 into alignment with their fixed tracks 1, the other ends of said rail sections 4 being guided in their movement by the stops 14 at that end. This movement of center plate 9 at the same time similarly shifts the rail sections 5 to the dotted line position, the single stops 14 therefore acting as pivots for the outer ends of said rail sections, though they move bodily with respect thereto to move away from their fixed tracks 2. It will thus be seen that by shifting lever 12 the tracks 1 or 2 may be completed at will.

Having thus described my invention, what I claim as new and desire to secure by Letters Patent is:

1. A railway crossing, embodying rail sections at the point of juncture of the tracks, said rail sections being bodily movable to and from their position of alignment, and means for simultaneously moving said rail sections so that those of one pair of tracks will be in alignment while those of the other pair of tracks will be out of alignment.

2. A railway crossing, embodying rail sections at the point of juncture of the tracks, said rail sections being bodily movable to and from their positions of alignment, a pivoted center plate connected to said rail sections; and means for operating said center plate to move said rail sections bodily into and out of alignment with their tracks, the rail sections of one pair of tracks moving into alignment as those of the other pair of tracks move out of alignment.

3. A railway crossing, embodying a pair of rail sections for each track of the crossing bodily movable to and from their position of alignment, a pivoted plate connecting the adjacent ends of each pair of rail sections, stops for guiding the movement of said rail

sections in their movement out of alinement and limiting their movement when in alinement, and means for simultaneously operating said rail sections to bring those of one pair of tracks in alinement, and to simultaneously bring the other pairs out of alinement.

4. A railway crossing, embodying a pair of rail sections for each track of the crossing 10 bodily movable to and from their position of alinement, a pivoted plate connecting the ends of each pair of rail sections, stops for guiding the movement of said rail sections 15 in their movement out of alinement and limiting their movement when in alinement,

a pivoted center plate, links connecting said pivoted plates with said center plate, and a lever for operating said center plate to shift said rail sections to bring those of one pair of tracks in alinement and to simultaneously bring the other pairs out of alinement. 20

In testimony whereof, I have hereunto set my hand in the presence of two subscribing witnesses.

BENJAMIN C. MEYER.
